(57) **CLAIM**

The ornamental design for a shopping bag carrier, as shown and described.

DESCRIPTION

FIG. 1 is a front perspective view of a shopping bag carrier showing my new design showing the carrier in its use mode; FIG. 2 is a rear perspective view of a shopping bag carrier showing my new design;

FIG. 3 is a rear elevational view thereof;

FIG. 4 is a front elevational view thereof;

FIG. 5 is a left side elevational view thereof;

FIG. 6 is a right side elevational view thereof.

FIG. 7 is a top plan view thereof;

FIG. 8 is a bottom plan view thereof;

FIG. 9 is a rear perspective view thereof showing the carrier in its closed position; and,

FIG. 10 is a sectional view taken along the lines 10—10 in FIG. 9.

The portions shown in broken lines in FIG. 1 are for information only and form no part of the claimed design.
